No. 721,821.

PATENTED MAR. 3, 1903.

C. O. MYERS.
REGULATING VALVE.
APPLICATION FILED MAR. 1, 1902.

NO MODEL.

UNITED STATES PATENT OFFICE.

CHARLES O. MYERS, OF PERRY, IOWA.

REGULATING-VALVE.

SPECIFICATION forming part of Letters Patent No. 721,821, dated March 3, 1903.

Application filed March 1, 1902. Serial No. 96,270. (No model.)

To all whom it may concern:

Be it known that I, CHARLES O. MYERS, a citizen of the United States, residing at Perry, in the county of Dallas and State of Iowa, 5 have invented certain new and useful Improvements in Regulating-Valves, of which the following is a specification.

The objects of my invention are to provide a valve of this class in which the passage-way 10 through the valve is obstructed only by a plate having different-sized openings therein, said openings capable of being successively brought into position coinciding with the passage-way through the valve, whereby the 15 greatest accuracy in regulating the capacity of the valve may be attained, and, further, to provide simple and durable means whereby the valve-plate may be adjusted and to provide simple indicating means by which the 20 operator may positively ascertain which one of the various openings is in position coinciding with the opening in the valve.

My invention consists in certain details in the construction, arrangement, and combination 25 of the various parts of the device, whereby the objects contemplated are attained, as hereinafter more fully set forth, pointed out in my claims, and illustrated in the accompanying drawings, in which—

30 Figure 1 shows in perspective the complete valve with a portion of a pipe connected with the union at one end thereof. Fig. 2 shows a vertical sectional view through one end portion of the valve-shell. Fig. 3 shows a vertical 35 central longitudinal sectional view of the complete device. Fig. 4 shows in perspective the plate detached from the valve.

Referring to the accompanying drawings, I have used the reference-numeral 10 to indicate 40 the body portion of the valve-shell. At one end thereof is an annular extension 11, designed to receive a wrench, and the shell is internally screw-threaded at 12. The other end portion of the shell is adapted to 45 form a union by having its exterior screw-threaded at 13 and a union-fitting 14 connected therewith to receive a pipe 15, said union being of ordinary construction. At the central portion of the shell is a vertical 50 extension 16, which projects both above and below the body portion of the shell. At its top is a detachable plate 17, and the interior

of the extension is hollow, forming a chamber 18. At the rear of the chamber 18 is a partition 19 within the body portion of the 55 cell having a comparatively small opening 20 therein.

The reference-numeral 21 indicates a plate of a size and shape designed to enter the opening in the interior of the extension 16 and of 60 such length as to be capable of considerable vertical movement therein. At the top of the plate 21 is a smooth flat surface 22, and beneath the surface 22 is a series of openings 23 of different sizes. At the front face of the 65 plate is a series of cog-teeth 24 at one side of the row of openings 23. When this plate is arranged within the chamber 18, it may move vertically within, so that any one of the openings 23 on the flat surface 22 may be brought 70 into position in line with the opening 20, and when the flat surface 22 is in line with the opening 20 the passage-way through the valve will be cut off, and when any one of the openings 23 is in line with the opening 20 the capacity 75 of the valve will be limited to that of the opening in the plate 21 which is in line with the opening 20.

To operate the plate 21, I have provided a shaft 25, seated in an extension 26 on the 80 side of the shell and having its outer end made annular at 27 to receive a key. On the inner end of the shaft 25 is a pinion 28 to mesh with the cog-teeth 24. Obviously when the shaft 25 is turned the plate 21 will be 85 moved vertically within the valve-shell.

I have provided means whereby the operator may ascertain with the greatest accuracy just which one of the openings 23 is in line with the opening 20 within the valve-shell, as 90 follows: On the outer end of the shaft 25 is an indicator 29, and on the extension 26, surrounding the shaft 25, is a series of marks 30, one mark being designed for each of the openings 23 and one for the flat surface 22, said 95 marks and indicator and pinion and teeth-plate being so arranged and proportioned relative to each other that when the indicator points to the mark 30 corresponding to any one of the openings 23 on the flat surface 100 22 said opening or flat surface will be in position in line with the opening 20.

In practical use and assuming my improved valve to be connected with water-pipes and

assuming that it is desired to permit a flow of water through the pipes such as would pass through the smallest one of the openings 23 the operator need only place a key upon 5 the annular end of the shaft 25 and turn said key to such position that the indicator 29 will point to the mark 30 corresponding with the smallest opening 23. Obviously the amount 10 of water permitted to pass through the valve would then be limited by the size of the opening, and any one of the openings may readily 15 and quickly be brought into position to coincide with the opening 20, or the flat surface 22 may be brought to this position, thus cutting off the flow of water through the valve. It is 20 obvious, further, that the back surface of the flat surface 22 may be made perfectly flat and that the interior of the extension 16 may also be made perfectly flat, so that a water-tight joint is provided between the back of 25 the plate 21 and the interior of the extension.

Having thus described my invention, what I claim, and desire to secure by Letters Patent of the United States therefor, is—

25 1. An improved regulating-valve, comprising a shell having an integral partition provided with an opening materially smaller in diameter than the interior of the shell, two hollow extensions on the shell one inner face 30 of each extension being flush with one face of the partition, a flat plate having one smooth face resting against the partition and the flush faces of the extensions to form a water-tight joint, said plate having a series of openings 35 of graduated sizes, each susceptible of

coinciding with the opening in the partition, cog-teeth formed on the face of the plate opposite from the partition, a pinion contained wholly within the shell, meshed with said cog-teeth, and a shaft for the pinion mounted in 40 the shell and projected through it.

2. An improved regulating-valve, comprising a shell having an integral partition provided with an opening materially smaller in diameter than the interior of the shell, two 45 hollow extensions on the shell one inner face of each extension being flush with one face of the partition, a flat plate having one smooth face resting against the partition and the flush faces of the extensions to form a water-tight joint, said plate having a series of openings 50 of graduated sizes, each susceptible of coinciding with the opening in the partition, cog-teeth formed on the face of the plate opposite from the partition, a pinion contained 55 wholly within the shell, meshed with said cog-teeth, a shaft for the pinion mounted in the shell and projected through it, an indicator on the shaft, and indicating-marks on the exterior of the shell corresponding to the openings in the plate, said marks and indicator coacting with the plate to indicate the position of its openings relative to the opening in the partition.

Des Moines, Iowa, December 12, 1901.

CHARLES O. MYERS.
